UNITED STATES PATENT OFFICE.

NEWTON J. BRANDEBERRY, OF SWANTON, OHIO.

COMBINED DUST AND WATER PROOF PROTECTOR FOR SHELF GOODS.

SPECIFICATION forming part of Letters Patent No. 515,141, dated February 20, 1894.

Application filed June 23, 1890. Serial No. 356,362. (No model.)

To all whom it may concern:

Be it known that I, NEWTON J. BRANDEBERRY, of Swanton, in the county of Fulton and State of Ohio, have invented certain new and useful Improvements in a Combined Dust and Water Proof Protector for Shelf Goods; and I do hereby declare that the following is a full, clear, and exact description of the invention, which will enable others skilled in the art to which it appertains to make and use the same, reference being had to the accompanying drawings, and to the figures of reference marked thereon, which form part of this specification.

15 This invention relates to a combined dust and water proof protector for shelf goods.

Heretofore, it has been customary to protect shelf goods against dust, and more particularly dry goods, by a curtain of a material the texture of which is sufficiently close to preclude the entrance of dust to the said goods, but not heavy enough to turn water. These curtains have usually been removably suspended upon hooks secured above the 25 shelving, which fastening is not of a nature to draw the curtains tightly against the shelves, but leaves a considerable space between them and the goods through which the dust settles. This is a source not only of much trouble, but also of considerable loss to dry goods merchants, inasmuch as the fold in double width goods such as cashmere, alpaca, merinos, &c., becomes discolored from the dust and frequent brushing to remove the same, thereby making 35 it necessary to sell them at a reduced rate in order to dispose of them at all. Moreover, it is a well known fact, that in case of fire it frequently happens that more goods are damaged by water than by the flames for the reason that such curtains are of no protection, as the water easily penetrates them and allows the goods to become saturated.

It is the object of this invention to overcome these obstacles by producing a curtain 45 which will at one and the same time be dust and water proof, and if desired fire proof, and which may be easily and rapidly brought into position to cover the goods completely, and in such a manner, that no dust can find its way 50 behind the same; furthermore, to produce a self removing curtain in contradistinction to

the ordinary kind which have to be put up every night, and taken down and folded away every morning.

With these objects in view, the invention 55 consists in providing a curtain adapted to move in guides or ways formed respectively in the molding and base of the shelving and connecting therewith mechanism for removing the said curtain from in front of the 60 shelving.

The invention further consists in providing a roller carrying a curtain of sufficient length to cover any given length of shelving, and connecting mechanism therewith for causing 65 the said roller automatically to remove the curtain from the front of the said shelving.

The invention further consists in providing a roller carrying a curtain of sufficient length to extend the entire distance of a series of 70 shelves, and actuating the said roller by a spring independent of the same.

The invention further consists in providing a spring actuated shaft carrying a pulley, a roller carrying a curtain, and connecting the 75 roller and shaft by a flexible connection, whereby, the unwinding of the curtain rotates the spring actuated shaft and thus stores up sufficient power to rewind the curtain to cause it to uncover the shelves. 80

The invention finally consists in the various novel details of construction of the said device, as will be hereinafter fully described in the specification, illustrated in the drawings, and more particularly pointed out in the 85 claim.

In the accompanying drawings, forming part of the specification, and in which like numerals of reference indicate corresponding parts, I have illustrated one form of device 90 embodying the essential features of my invention, although the same may be carried into effect in other ways without in the least departing from the spirit thereof, and in the drawings— 95

Figure 1 is a perspective view of a section of shelving showing the curtain placed thereon. Fig. 2 is a vertical transverse sectional view, showing more particularly the guides or ways in which the curtain moves. Fig. 3 100 is an end view of the shelving, showing more particularly the guide roller, and roller car-

rying the curtain, and Fig. 4 is a bottom plan view showing the roller operating mechanism.

Referring to the drawings, 1, designates a section of shelving, which may be of any desired length. At one end of the section, are secured in a suitable manner two plates 2 and 3, in which are journaled respectively a spring actuated roller 4, and a guide roller 5. To the lower end of the roller 4, is secured a pulley 6, to which is connected a cord or chain 7, the opposite end of which is secured to a pulley 8, mounted upon a shaft 9, which shaft is actuated by a spring 10 rigidly secured thereon. The spring and pulley are arranged within a suitable boxing 11, mounted below the base 12, of the shelving.

Within the base 12, and molding 13, are arranged guides or ways 14 and 15, in which move cords 16, secured within pockets formed respectively in the upper and lower edges of the curtain 18 which cords move freely within the said guides, but are too large to be drawn out through the recess in which the curtain moves.

Having thus fully described my invention, I will explain the manner of its operation: In setting up the device, the two pulleys 6 and 8, are so arranged with relation to each other, that one revolution of the pulley 8, will cause the pulley 6 to revolve say six times. This arrangement is necessary, inasmuch as it would be extremely difficult to furnish springs which would have a winding capacity of say one hundred and twenty feet, which is frequently the length of a single section of shelving in large stores. The size of the two rollers may however be varied to meet the requirements of the case. When the device is to be used, the operator grasps a strengthening piece 17, secured to the free end of the curtain, and runs out the same the entire length of the shelving, and secures the free end in any suitable manner to the end of the

shelving. When it is desired to uncover the 45 shelving, the free end of the curtain is released, when the spring will automatically rewind the same upon the roller.

As stated in the first part of this specification, the curtain is to be of sufficient heft to 50 turn water, and for this purpose a canvas cloth is preferable. Moreover the utility of this device may be highly increased by coating the curtain with a refractory paint or varnish, whereby, the curtain will serve a three-fold purpose, that of a dust, water and fire proof protector. If desired also the rollers 5 and 4 may incased in such manner as to be invisible.

Having thus fully described my invention, 60 what I claim as new, and desire to secure by Letters Patent, is—

The combination with the shelving having parallel horizontal grooves formed in the molding and base of the same, a casing arranged in one corner of the shelving the horizontal shaft journaled within the casing, a coiled spring attached to said shaft, a grooved roller also mounted upon said shaft, the horizontal brackets attached to one end of the 70 shelving, the vertical curtain roll, journaled between the brackets at a point to the rear of the grooved roller on the horizontal shaft, the vertical guide roll journaled also between the brackets opposite the horizontal grooves 75 in the molding and base, the cord wound upon the horizontal roller and the lower end of curtain roller and passing through a perforation in the case, and the curtain having corded edges adapted to run in the horizontal groove 80 in the molding and base.

In testimony that I claim the foregoing as my own I hereby affix my signature in presence of two witnesses.

NEWTON J. BRANDEBERRY.
